UNITED STATES PATENT OFFICE.

JOHN A. LAMONT, OF CHICAGO, ILLINOIS, ASSIGNOR TO AMERICAN STEEL FOUNDRIES, OF CHICAGO, ILLINOIS, A CORPORATION OF NEW JERSEY.

BOLSTER FOR SIX-WHEEL TRUCKS.

Application filed May 4, 1923. Serial No. 636,541.

To all whom it may concern:

Be it known that I, JOHN A. LAMONT, a citizen of the United States, residing at Chicago, in the county of Cook and State 5 of Illinois, have invented certain new and useful Improvements in Bolsters for Six-Wheel Trucks, of which the following is a specification.

This invention relates to a bolster for a 10 six wheel truck.

The single integrally formed truck bolster having four legs as used in connection with six wheel trucks does not always properly equalize the load transmitted through the 15 center plate. In such a bolster on account of its rigidity the load under certain truck conditions may be concentrated on three or possibly two of the four legs, which tends to defeat other equalizing features there may 20 be in the truck.

To facilitate load distribution there was provided a three piece bolster for six wheel trucks as disclosed in my Patent No. 1,877,- 706, granted May 10, 1921.

One object of my present invention is to 25 provide a bolster which is reasonably flexible to facilitate a relatively uniform distribution of the central plate load to the springs and at the same time simplify the construction shown in said patent and reduce the 30 weight and cost of bolsters for six wheel trucks.

Another object is to provide a bolster for 35 six wheel trucks which is simple and durable in construction and adapted to meet the various requirements of actual service conditions.

These and other objects are accomplished 40 by means of the arrangement disclosed on the accompanying sheets of drawings, in which—

Figure 1 is a top plan view of a truck bolster embodying my invention;

Figure 2 is a side elevation of said bolster;

Figure 3 is a sectional view taken in the 45 plane of line 3—3 of Figure 1;

Figure 4 is a sectional view taken in the plane of line 4—4 of Figure 1;

Figure 5 is an elevation of one end of the 50 truck;

Figure 6 is a sectional view taken in the plane of line 6—6 of Figure 1; and

Figure 7 is an elevation of the end of the truck opposite to that shown in Figure 5.

The various novel features of the inven-

tion will be apparent from the following description and drawings and will be particularly pointed out in the appended claims.

Referring to the figures of the drawings, it will be noted that I have disclosed my invention in connection with a truck bolster for six wheel trucks including a transverse bolster member 10 and a second transverse bolster member 11, the ends of which are adapted to rest directly upon supporting 60 springs, said transverse bolster members being provided with lugs 12 for assisting in positioning said springs, not shown. The bolster also includes two longitudinally extending members 13, the corresponding ends 65 of which are formed integrally with one of said transverse bolster members 10, the other corresponding ends of the longitudinal bolster members 13 terminating in a transverse saddle portion or girder 14 which is 70 rockably mounted upon the transverse bolster member 11. The ends of the transverse saddle member 14 are provided with bearings 15 cooperating with stop portions 16 on said transverse bolster member 11 for 75 limiting the relative rocking movements therebetween, and the ends of said saddle member 14 cooperate with stop shoulders 17 for limiting relative transverse movements of said longitudinal bolster members 13 and 80 transverse bolster member 11. The saddle portion 14 includes downwardly extending legs 18' which straddle the transverse bolster member 11 for definitely positioning the longitudinal members 13 with respect to the 85 transverse bolster member 11 for preventing the bolster portions from getting out of square. Formed integrally with the longitudinal bolster members 13 are upstanding brackets having side bearings 18.

The equalizing bolster, in addition to including the longitudinal bolster members 13 and the transverse girder or saddle member 14, includes the center plate member 19, which in this particular instance I have 100 chosen to make in a separate piece to facilitate production, and, as a matter of fact, such piece, when cast separately, can be made of lighter sections and with a smoother center plate than is practical when this 105 portion is cast integrally with the other associated portions. This center plate member 19 is designed to bear directly on the longitudinally extending bolster members 13 and is secured in place by rivets 20 and 110

against longitudinal movement by lugs 21 which engage within wall portions 22 on the side bearing brackets 18.

This type of bolster may properly be termed a three-point bearing bolster, the ends of the transverse or fixed bolster member 11 resting directly upon the associated springs (not shown) and the third bearing being that of the saddle or girder 14 rockably mounted upon the transverse bolster 11. It is apparent that this construction insures a more uniform distribution of the center plate load to the various springs than is possible with the integrally formed truck bolster having four corner legs which bear upon the four associated sets of springs. At the same time this present bolster arrangement provides for a reduction in the weight over the three-piece bolster arrangement disclosed in my above-mentioned patent by reason of the omission of the saddle portion at one end and the change in distribution of load on the cross bolster member 19 at that end, the load being delivered near the points of support instead of at the center, as is the case at the other end where the transverse girder or saddle member 14 is rockably supported on the transverse bolster member 11.

It is my intention to cover all modifications of the invention falling within the spirit and scope of the following claims.

I claim:

1. A railway car truck bolster, including, in combination, two cross bolster members and a plurality of longitudinally extending bolster members integrally formed with one of said cross bolster members and having a connecting girder rockably associated with the other cross bolster member for equalizing the transmitted load.

2. A railway car truck bolster, including, in combination, two cross bolster members and a plurality of other bolster members integrally formed with one of said cross bolster members and having a connecting girder rockably associated with the other cross bolster member for equalizing the transmitted load.

3. A railway car truck bolster, including, in combination, two cross bolster members, a plurality of other bolster members integrally formed with one of said cross bolster members and having a connecting girder rockably associated with the other cross bolster member for equalizing the transmitted load, and a center plate member supported by said other bolster members.

4. A railway car truck bolster, including, in combination, two cross bolster members, a plurality of longitudinally extending

bolster members integrally formed with one of said cross bolster members and having a connecting girder rockably associated with the other cross bolster member for equalizing the transmitted load, and a separate center plate member secured to said longitudinally extending bolster members. 65

5. A railway car truck bolster, including, in combination, two cross bolster members, a plurality of other bolster members extending in a different direction from that of the cross bolster members and integrally formed with one of said cross bolster members and rockably associated with the other of said cross bolster members for equalizing the transmitted load, said other bolster members having side bearing members integrally formed therewith, and a separate center plate member connecting said other bolster members and prevented from displacement by being interconnected with said side bearing members. 70 75 80

6. A railway car truck bolster, including, in combination, two cross bolster members, two longitudinally extending bolster members integrally formed with one of said cross bolster members and having a connecting girder rockably associated with the other of said cross bolster members for equalizing the transmitted load, side bearing members integrally formed with said longitudinally extending bolster members, and a center plate bolster member spanning said longitudinally extending bolster members and interconnected therewith to prevent accidental displacement with respect thereto. 85 90 95

7. A railway car truck bolster, including, in combination, two cross bolster members, a plurality of other bolster members integrally formed with one of said cross bolster members and having a rockable association with said other cross bolster member for equalizing the transmitted load, and means for limiting said rocking motion by interengagement of said last mentioned cross bolster member with said other bolster members. 100 105

8. A railway car truck bolster, including, in combination, two cross bolster members, a plurality of longitudinally extending bolster members integrally formed with one of said cross bolster members and having a connecting girder rockably associated with the other of said cross bolster members for equalizing the transmitted load, said rocking movement being limited by interengagement of one of said cross bolster members and said girder member. 110 115

Signed at Chicago, Illinois, this 30th day of April, 1923.

JOHN A. LAMONT.
